United States Patent Office

Des. 229,873

Patented Jan. 8, 1974

229,873

TIRE

Eugene E. McMannis, Cuyahoga Falls, Ohio, assignor to
Max-Trac Tire Co., Inc.

Filed Feb. 17, 1972, Ser. No. 227,344

Term of patent 14 years

Int. Cl. D12—15

U.S. Cl. D90—20 R

FIG. 1

FIG. 2

FIG. 3

FIG. 4

FIG. 5

FIG. 1 is a perspective view of the tire of my new design;

FIG. 2 is a fragmentary plan view;

FIG. 3 is a fragmentary side view;

FIG. 4 is a fragmentary vertical section on line 4-4 of FIG. 2; and

FIG. 5 is a fragmentary enlarged section on line 5-5 of FIG. 3.

The tread design shown is repeated throughout the circumference of the tire and the side opposite to that shown is the same.

I claim:

The ornamental design for a tire, as shown and described.
